UNITED STATES PATENT OFFICE.

NOYES F. PALMER, OF BROOKLYN, NEW YORK.

MACHINE FOR MOLDING ARTIFICIAL STONE.

SPECIFICATION forming part of Letters Patent No. 703,452, dated July 1, 1902.

Application filed April 22, 1902. Serial No. 104,144. (No model.)

To all whom it may concern:

Be it known that I, NOYES F. PALMER, a citizen of the United States, and a resident of Brooklyn, county of Kings, and State of New York, have invented certain new and useful Improvements in Machines for Molding Artificial Stone, of which the following is a specification.

This invention relates to an improved machine for molding artificial concrete building and paving blocks, and more particularly to an improved construction of adjustable cores by means of which the machine may be readily set to turn out blocks of various sizes and configurations.

In the accompanying drawings, Figure 1 is a side elevation of my improved machine for molding artificial stone; Fig. 2, a top view of the core-support; Fig. 3, a top view of the mold-box with the false bottom removed; Fig. 4, a longitudinal section taken on line 4-4, Fig. 3; Fig. 5, a cross-section on line 5-5, Fig. 3; and Figs. 6 and 7 are perspective views illustrating two of the forms of blocks that may be molded by the machine.

The letter *a* represents the frame of the machine, and *a'* is the base-plate that forms the bottom of the mold-box. The sides *b* and ends *c* of the mold are adapted to slide upon the base-plate, so as to open or close the mold. This movement is effected from shaft *d* by bevel-gear *d'* and racks *b' c'*, such construction, however, not forming part of the present invention.

The base-plate *a'* has a central opening adapted to accommodate a longitudinally-slotted plate *e*, that constitutes a support for the cores *f*, used in making hollow blocks. These cores are adapted to be removably and adjustably secured to the support *e*, so that by shifting or interchanging the cores a variety of blocks may be molded by one and the same machine. In order to permit the cores to be readily locked and unlocked and to be shifted along the base-plate, I have devised the following construction: Each core *f* is hollow and perforated at the top and bottom. Through the perforations extend upright bolts *g*, that project below the cores and into the slot *e'* of plate *e*, to which they are held by heads *g'*. The threaded upper end of each bolt carries a nut *g''*, counter-

sunk within the top plate of the core. By slackening the nut the core is unlocked from the base-plate and may be shifted along the same by sliding the bolt along the slot *e'* until the core arrives at its new position, when it may be relocked by tightening up the nut. Thus it will be seen that the cores may be readily adjusted and that the locking and unlocking mechanism is readily accessible from the top of the machine.

Each core is preferably subdivided transversely into two sections for the introduction of transverse partitions *h*, used in molding blocks shorter than the mold. In order to permit the molding of blocks narrower than the mold, I employ longitudinal partitions *h'*, which are inserted between adjoining cores. To this effect the cores are provided with grooves *f'*, that face each other and into which the partitions may be slid. The ends *c* of the mold may also be grooved, as at *c''*, to engage the last partition, and they may likewise be provided with curved projections or cores *c''* if a block with a curved end is to be molded. Thus with the setting of cores and partitions indicated in Fig. 3 two blocks A, Fig. 6, will be turned out by the left half of the mold, while one block B, Fig. 7, will be turned out by the right half.

The support *e* may be made vertically movable, so that the cores may be withdrawn downward from out of the mold. This movement is effected by a shaft *i*, pinions *i'*, and racks *i''*.

Upon the mold-bottom *a'* is placed a false bottom *j*, which is perforated to accommodate the cores and cover the exposed section of slot *e'*. This false bottom may be raised so as to discharge the finished block over the top of the mold, the vertical movement being imparted to it from shaft *i*, through pinions *j'*, and racks *j''*, that pass through openings *a''* of base-plate *a'*.

It will be seen that by my invention the mold may be set to shape a large variety of blocks and that the adjustment of the mold can be effected in a simple and convenient manner.

What I claim is—

1. In a machine for molding artificial stone, the combination of a mold with a slotted supporting-plate, an adjustable core, and a bolt

extending through the core and engaging the slotted plate, substantially as specified.

2. In a machine for molding artificial stone, the combination of a mold with a supporting-
5 plate having a longitudinal slot, an adjustable core, a headed bolt extending through the core and engaging the slotted plate, and a nut engaging the upper end of the bolt, substantially as specified.
- 10 3. In a machine for molding artificial stone, the combination of a mold with an adjustable grooved core, and with a partition engaging the core-groove, substantially as specified.

4. In a machine for molding artificial stone, the combination of a mold with a slotted supporting-plate, an adjustable grooved core, a bolt extending through the core and engaging the slotted plate, and a partition engaging the core-groove, substantially as specified. 15

Signed by me at New York city, New York, 20 this 21st day of April, 1902.

NOYES F. PALMER.
